Primary Examiner — Janice Hallmark(74) *Attorney, Agent, or Firm* — Dentons US LLP(57) **CLAIM**

The ornamental design for a storage caddy, as shown and described.

DESCRIPTION

FIG. 1 is a front perspective view of a first embodiment of the design.

FIG. 2 is a front view of the design of FIG. 1.

FIG. 3 is a right-side view of the design of FIG. 1, the left-side view being a mirror image thereof.

FIG. 4 is a top view of the design of FIG. 1.

FIG. 5 is a bottom view of the design of FIG. 1.

FIG. 6 is a front perspective view of a second embodiment of the design.

FIG. 7 is a front view of the design of FIG. 6.

FIG. 8 is a right-side view of the design of FIG. 6, the left-side view being a mirror image thereof.

FIG. 9 is a top view of the design of FIG. 6; and,

FIG. 10 is a bottom view of the design of FIG. 6.

The broken lines in the drawings depict environmental subject matter only and form no part of the claimed design.
